CORRUGATED ICE COMPARTMENT

Horace Giddings, San Francisco, Calif.

Application March 26, 1938, Serial No. 198,293

7 Claims. (Cl. 62—19)

The present invention relates to refrigerator cars, and especially to the construction of the ice compartments or tanks thereof.

The principal object of the invention is to provide an ice compartment in which the surface exposed to contact with the ice on one side and with the circulating air on the other side is as large as possible, in order to effect rapid transfer of heat from said air. This is accomplished by forming the walls of the ice compartment of vertically corrugated sheet metal. The ice, being broken into irregular small pieces when loaded, partially fills the interior corrugations of the wall, which therefore has a greater surface area in contact with the ice than would be the case with a flat wall. As the ice melts, it further fills said interior corrugations.

Another object of the invention is to provide for the greatest possible circulation of air through and around the ice compartment and between it and the lading compartment of the car. The vertically corrugated lining walls themselves contribute to the achievement of this object, by providing vertical air channels between their corrugations and the adjacent walls of the car. Numerous apertures are provided in the corrugated walls, through which air may freely pass between said channels and the interior of the ice compartment. The lower ends of said channels are open to the space beneath the ice grate within the ice compartment.

The free circulation of air between the lading and ice compartments is further assisted by the construction of that wall of the ice compartment which separates it from the lading compartment. This wall, commonly termed the bulkhead, is in my construction formed of vertically corrugated sheet metal similar to the other walls of the compartment, and is secured to the sides and inner roof or ceiling of the car, its lower edge being spaced above the floor and entirely clear thereof, the space between said bulkhead and the floor being open and free of any posts or other obstructions to the movement of air. The corrugated bulkhead sheet forms a suspension support for the forward edge of the ice grate on one side and for the usual bulkhead pad on the other side, said pad being preferably a solid wooden panel extending across the car and spaced from both the floor and the ceiling. Above said pad, the corrugated bulkhead sheet is provided with a plurality of apertures of special vertically elongated form, which offer the least possible obstruction to the free movement of air from the

upper portion of the lading compartment to the upper portion of the ice compartment.

Another object of the invention is to prevent water and chips of ice from splashing and flying out of the ice compartment into the air passages and into the lading compartment. For this purpose the apertures in the corrugated walls are narrow and are provided with deflecting tongues and lips which catch drops of water and chips of ice and return them to the interior of the ice compartment. Moreover, the bottom of the corrugated bulkhead wall is formed in a novel manner designed to direct the drip from said wall inwardly toward the drip pan in the bottom of the ice compartment and away from the floor of the lading compartment.

By providing corrugated and apertured walls for the ice compartment, I eliminate the necessity for using screens at any point. The corrugated bulkhead wall, formed with my novel apertures in its upper portion, is a unitary structure, permitting free circulation of air and preventing pilfering of the lading from the ice compartment, without necessitating the usual additional section of screen covering the open space above the bulkhead pad. The entire ice compartment is constructed economically of machine-made light-weight corrugated sheets. I also make the ice grate of corrugated and perforated sheet metal.

These and other objects and advantages of the invention will be made more apparent by the following description, which should be read with the understanding that changes, within the scope of the claims hereto appended, may be made in the form, construction and arrangement of the several parts herein shown and described, without departing from the spirit of the invention.

In the drawings, Fig. 1 is a vertical longitudinal section of the end portion of a refrigerator car, showing an ice compartment therein embodying a preferred form of the present invention.

Fig. 2 is a horizontal section of the same taken approximately on the line 2—2 of Fig. 3, the ice grate being omitted from the right hand portion.

Fig. 3 is a transverse vertical section of the same, taken on the line 3—3 of Fig. 2.

Fig. 4 is an enlarged horizontal section of the upper portion of the bulkhead wall.

Referring in more detail to the drawings, the reference numeral 10 designates the end wall of a refrigerator car, 11 is the floor thereof, 12

- solid portion spaced from the floor and the roof of the car, a lining for said wall comprising a vertically corrugated sheet having its upper edge secured to said roof and its lower edge spaced 5 from said floor, the corrugations of said sheet forming air channels between said sheet and the solid portion of said wall, said sheet having a plurality of vertical slots between the upper edge of the solid portion of said wall and said roof to 10 permit air to pass freely between said compartments, the portions of the sheet between said slots being curled inwardly to form splash guards and to provide vertical drain channels facing toward the ice compartment.
- 15 3. In a refrigerator car having an ice compartment and lading compartment, a bulkhead between said compartments comprising a vertically corrugated sheet secured to the roof of the car and extending downwardly therefrom, the lower 20 edge of said sheet being spaced from the floor of the car and said lower edge being serrated, the inner corrugations projecting into the ice compartment being cut out and the intervening outer corrugations being bent inwardly at their 25 lower ends, and the upper portion of said sheet having a plurality of apertures to permit free circulation of air between said compartments.
4. In a refrigerator car having an ice compartment a lining member for said compartment comprising a sheet of metal having a plurality of elongated approximately vertical slots, said slots being spaced apart laterally and the portions of the sheet between said slots being curled inwardly to form splash guards and to provide concave 30 35
- drain channels facing inwardly toward the compartment.
5. In a refrigerator car having an ice compartment and a lading compartment, a bulkhead between said compartments comprising a sheet of metal extending downwardly from the roof of the car, said sheet having a row of approximately vertical elongated slots in its upper portion, said slots being spaced laterally and having their edges bent inwardly toward the ice compartment to 10 form splash guards for said slots.
6. In a refrigerator car having an ice compartment, a lining member for a wall of said compartment comprising a sheet of metal having a serrated lower edge forming a plurality of downwardly extending pointed tongues, the side edges and the lower ends of said tongues being bent toward the compartment to form inwardly inclined drain channels, whereby water draining down the surface of said sheet is directed inwardly away from the compartment wall.
7. In a refrigerator car having an ice compartment and a lading compartment, a bulkhead between said compartments comprising a sheet of metal extending downwardly from the roof of the car, the upper portion of said sheet having a plurality of apertures to permit passage of air between said compartments, the lower edge of said sheet being spaced from the floor of the car, and said lower edge having portions bent inwardly toward the ice compartment to form drain channels whereby water draining down the surface of said sheet will be directed away from the lading compartment.
